US0D1086712S

(12) **United States Design Patent** (10) **Patent No.:** **US D1,086,712 S**
(45) **Date of Patent:** **** Aug. 5, 2025**

(54) **MESH BASKET**

(71) Applicant: **Design Ideas, Ltd.**, Springfield, IL (US)

(72) Inventors: **Christopher Hardy**, Springfield, IL (US); **Richard Kromer**, Morton Grove, IL (US)

(73) Assignee: **Design Ideas, Ltd.**, Springfield, IL (US)

(**) Term: **15 Years**

(21) Appl. No.: **29/933,465**

(22) Filed: **Mar. 20, 2024**

Related U.S. Application Data

(60) Continuation of application No. 29/749,347, filed on Sep. 4, 2020, now Pat. No. Des. 1,032,205, which is a continuation of application No. 29/647,367, filed on May 11, 2018, now Pat. No. Des. 895,969, which is a continuation of application No. 29/527,940, filed on May 22, 2015, now abandoned, which is a continuation of application No. 29/207,480, filed on Jun. 16, 2004, now abandoned, which is a division of application No. 29/206,724, filed on Jun. 1, 2004, now Pat. No. Des. 530,517, which is a continuation of application No. 29/148,324, filed on Sep. 19, 2001, now abandoned, which is a continuation-in-part of application No. 29/115,615, filed on Dec. 16, 1999, now Pat. No. Des. 451,675, which is a division of application No. 29/092,939, filed on Aug. 31, 1998, now Pat. No. Des. 419,302.

(57) **CLAIM**

The ornamental design for a mesh basket as shown and described.

DESCRIPTION

The sole FIGURE is a front view of a mesh basket showing our new design.

The dashed broken lines illustrate structure or features which form no part of the claimed design. The dot-dash broken lines illustrate an unclaimed boundary.

1 Claim, 1 Drawing Sheet
